United States Patent Office.

FERDINAND KILSHEIMER, OF CINCINNATI, OHIO.

Letters Patent No. 102,946, dated May 10, 1870.

IMPROVEMENT IN SHOES.

The Schedule referred to in these Letters Patent and making part of the same.

To all whom it may concern:

Be it known that I, FERDINAND KILSHEIMER, of Cincinnati, in the county of Hamilton and State of Ohio, have invented certain new and useful Improvements in Shoes; and I do hereby declare that the following is a full, clear, and exact description thereof, reference being had to the annexed drawing making a part of this specification, in which—

Figure 1 represents the shoe unbuckled and heel-strap erect.

Figure 2 shows the heel-strap turned down, and Figure 3 represents the shoe buckled around the ankle.

Similar letters of reference indicate like parts.

The nature of my invention relates to that class of shoes in which the front piece is crimped and formed of one piece, and the back part is formed so as to give ample room for the instep when the shoe is pulled on or off.

My improvement consists in forming the back part of the shoe in one piece including the strap for pulling on the same, there being no seam to prevent the foot from entering the shoe freely. The advantages of my invention are that the shoe may be worn buckled or unbuckled, increased strength owing to the absence of seams, simplicity of construction, and is also lighter, owing to the few parts used.

The shoe may be constructed of any material, according to the following description:

A and Bare the uppers, held together by the seam *a*.

The part *b* is an extension of the part *B*, and is of sufficient length to be passed through the buckle *C*, and in width so that, when doubled, to fill the buckle *C*.

The stiffening is inserted between the lining and the part *B*, presenting an even surface on the interior.

In operation my improvement becomes obvious: In wearing loose pantaloons the flap *b* may remain erect, as shown in fig. 1, or the flap *b* may be turned down, as seen in fig. 2.

In wearing the pantaloons tight, or from other reasons, the flap *b* may be buckled as represented in fig. 3.

It will also be observed that the strap *b* may be brought to any degree of tightness; owing to the seamless construction of part *B*, it will form a joint at any desired point.

In putting on the shoe there can be no reasonable chance of tearing the same, as no seams intervene to prevent the foot sliding freely into the shoe, while the strap *b*, being the part by which the shoe is pulled, also tends to keep the rear part of the same even and stiff.

In this shoe all the beauty and neatness of a boot is preserved, while it has at the same time the advantage of being simple, cheap, light, and capable of being worn tight or loose, while its exceeding simplicity adds greatly to its strength and neatness.

Having thus described my invention,

What I claim as new, and desire to secure by Letters Patent, is—

A shoe having the rear upper formed of one piece, with an extension, *b*, for the purpose of pulling on and buckling the same, substantially as herein described.

F. KILSHEIMER.
